UNITED STATES PATENT OFFICE

GEORGE W. BURGESS, OF BOSTON, MASSACHUSETTS.

SEWING-MACHINE TENSION DEVICE.

SPECIFICATION forming part of Letters Patent No. 254,794, dated March 14, 1882.

Application filed July 5, 1881. (No model.)

To all whom it may concern:

Be it known that I, GEORGE W. BURGESS, of Boston, in the county of Suffolk and State of Massachusetts, have invented certain new and useful Improvements in Sewing-Machine Thread-Tension Devices, of which the following is a specification.

The object of my invention is to provide an automatic thread-tension device which shall control the tension equally the same with a fine or coarse thread employed in the needle or shuttle, or with either one fine or coarse, or, however much the two threads may vary as to size or quality, the tension shall remain the same as desired upon each thread at all times; and it consists in the construction, combination, and arrangement of two journaled disks or wheels, the inner faces or surfaces of which are adapted to be revolved at a slight angle or inclination with each other by the passage of the thread between the same at or near their peripheries, the angle of inclination being automatically adjusted by the size of thread acting between such faces of the disks or wheels, which are held together at the desired pressure by the influence of a suitable spring, as hereinafter more fully described and set forth.

Figure 1 represents a perspective view of my invention applied to the latch of a shuttle, the latch being thrown out of position. Fig. 2 represents a top plan view of the same with the latch in position for use. Fig. 3 represents a horizontal section of the same. Fig. 4 represents an elevation of the same. Fig. 5 is a horizontal section of tension device enlarged.

A represents a sewing-machine shuttle provided with a latch, B, pivoted to the heel of the shuttle, and provided with a thread-eye, C, as heretofore, the thread E leading from the bobbin H through said eye C, and thence between the rotary wheels or disks F and L, and thence around the bearing or carrier near the periphery of said wheels, and thence back through the said eye C again, as shown. The wheel F is adapted to be revolved upon the journal or pin P, secured to the said latch B and projecting within the shuttle A, said pin

being flattened upon one side and provided with a wedge-shaped piece, R, which is provided with a hole corresponding with the form of the pin P, so as to prevent it from turning thereon, the point of the wedge-piece R being placed toward the point of the shuttle. Then the disk or wheel L is placed upon the said journal or pin P, upon which it fits loosely, and is retained thereon by the flat steel spring T, adjustably secured to the shuttle-latch B, as heretofore, its free end being provided with a hole, which passes over the exposed end of the said journal or pin P and rests upon the said disk or wheel L, opposite the point end of the wedge-piece R, and thereby inclines the said disk or wheel L at that side, so as to permit the thread to enter between the said wheels F and L at the opposite side, and thus cause it to impinge upon the thread E as it is drawn through between the said wheels F and L, thereby rotating the same, but not in the same plane, which plane varies according to the size of the thread, which is retained near the peripheries of the said wheels F and L by a series of pins, S, which project at right angles from the face of one of said disks, to which they are secured, and pass through corresponding holes formed in the opposite disk; or one of the said disks may be provided with a circular projecting rib or flange and the opposite disk provided with a corresponding groove, whereby the same result may be accomplished; or any other suitable means may be employed to serve the purpose contemplated.

It will be seen and understood that this tension device controls the lower or shuttle thread, and that an exact duplicate tension device may be arranged to control the upper or needle thread and connected with the needle arm, bar, or any other part of the machine where tension devices are usually connected, or at any point desired between the upper spool and the needle adapted to serve the purposes contemplated. Therefore I have omitted to illustrate the same, as my invention need not be further described, as its construction and operation are substantially the same in either case, shuttle-machines, or those using an upper and under thread, known as "double-threaded"

machines, requiring two tension devices, and "single-thread" machines requiring only one tension device, as heretofore.

Having thus described my invention, what 5 I claim is—

A sewing-machine rotary thread-tension consisting of the wheels or disks F and L, adapted to be rotated upon the journal or pin P at a slight angle of inclination with each other by

means of the wedge R and spring T, whereby 10 the tension of the thread passing between the same near their peripheries may be automatically regulated, substantially in the manner described, as and for the purposes set forth.

GEORGE W. BURGESS.
